UNITED STATES PATENT OFFICE.

THOMAS S. VOSBIKIAN AND PETER S. VOSBIKIAN, OF PHILADELPHIA, PENNSYLVANIA.

DESIGN FOR AN AUTOMOBILE BUMPER.

Application filed May 31, 1927. Serial No. 22,259. Term of patent 7 years.

To all whom it may concern:

Be it known that we, THOMAS S. VOSBIKIAN and PETER S. VOSBIKIAN, citizens of the United States, residing at Philadelphia, in the county of Philadelphia and State of Pennsylvania, have invented a new, original, and ornamental Design for an Automobile Bumper, of which the following is a specification.

The figure is a perspective view of our design of a bumper.

We claim:

The ornamental design for an automobile bumper substantially as shown.

THOMAS S. VOSBIKIAN.

PETER S. VOSBIKIAN.
